UNITED STATES PATENT OFFICE.

SZYMON SLOBODZIAN AND JOZEF OBERLEYTAN, OF NEWARK, NEW JERSEY.

MATCH-BOX.

1,359,759.

Specification of Letters Patent. Patented Nov. 23, 1920.

Application filed March 8, 1920. Serial No. 363,969.

To all whom it may concern:

Be it known that we, SZYMON SLOBODZIAN and JOZEF OBERLEYTAN, citizens of Poland, residing at Newark, in the county of Essex and State of New Jersey, have invented certain new and useful Improvements in Match-Boxes, of which the following is a specification.

This invention relates to certain new and useful improvements in match boxes of that type involving means to deliver matches one at a time to a person through manual actuation.

The principal object of the present invention is to provide a match delivering receptacle with associated delivering mechanism of such character as to be extremely durable and efficient in operation as well as simple in construction for cheapness of manufacture.

With the above general objects in view and others that will become apparent as the nature of the invention is better understood, the same consists in the novel form, combination and arrangement of parts herein fully described, shown in the accompanying drawings, and claimed.

In the drawings forming a part of this specification, and wherein like reference characters indicate similar parts throughout the several views,

Figure 1 is a front elevational view, partly broken away, of a match box constructed in accordance with the present invention,

Fig. 2 is a vertical sectional view taken substantially upon line II—II of Fig. 1,

Fig. 3 is a vertical sectional view of the device shown in Fig. 1 and taken substantially upon line III—III of Fig. 4,

Fig. 4 is a horizontal sectional view taken substantially upon line IV—IV of Fig. 3, and

Fig. 5 is an enlarged perspective view of the lever actuated pawl carrying member which actuates the ratchet wheel and a portion of the actuating lever therefor.

Referring more in detail to the several views, the present invention embodies a vertical elongated receptacle or casing 5, the rear vertical wall of which is extended some distance above and below the top and bottom thereof and is provided with apertures

6 into which nails or other suitable holdfast devices are adapted to be driven for fastening the box to the wall. The receptacle or casing 5 is provided with a vertical partition 7 so as to form a vertical chamber 8 at one side of the receptacle, and the partition 7 is connected with the opposite side wall of the receptacle by means of a horizontal partition 9 whose upper face is rearwardly and downwardly inclined as at 10 to insure movement of the matches 11 downwardly toward the drum 12. The partition 9 forms upper and lower compartments at 65 one side of the chamber 8, the upper compartment being in the form of a hopper having a lid 13 which may be hinged as at 14 so that the said cover may be raised for refilling the hopper when found necessary. 70 The lower compartment above mentioned contains the drum 12, and this drum is provided with a series of peripheral transverse grooves 15 which are, in practice, made of such size as to allow only one match to 75 fall thereinto at a time, although the showing in the drawing is somewhat exaggerated to clearly show the structure. The partition 9 is provided with an opening as seen in Fig. 2 so as to permit the matches 11 80 to pass from the hopper 16 onto the periphery of the drum 12, and this partition is curved on its underside so as to conform to the shape of the drum 12 and lie quite close to the periphery of the latter. 85

The drum 12 is secured upon a shaft 17 which is mounted for rotation horizontally in any suitable manner in the side walls of the receptacle 5, and the drum 12 is reduced at its inner side to provide a circular hub 90 18 which is rotatably fitted in a similarly shaped opening 19 provided in the partition 7. The drum 12 is provided with a still further reduced portion 20 which extends into the chamber 8 and has a ratchet wheel 95 21 fastened thereon.

A block 22 is vertically slidable within the chamber 8 beneath the shaft 17, and this block is normally retained in lowered position against the bottom of the receptacle 5 by means of a coiled tension spring 23 which has one end fastened as at 24 to the bottom of the receptacle 5 and which is fastened at its other or upper end to the top

of the block 22 by means of the screw 25 or the like. A pin 26 projects upwardly from the upper end of the slide block 22 so as to engage the radial face of one tooth of the ratchet wheel 21 when the parts are normally disposed as shown in Fig. 3, thereby preventing retrograde movement of the drum 12, and so as to impart movement to the drum 12 in the direction of the arrow —a— as shown in Fig. 2. A spring metal pawl 27 formed of resilient sheet metal is fastened to the block 22 adjacent one side of the latter, and this pawl projects upwardly beyond the upper end of the block 22 and has its upper end angularly bent rearwardly as at 28 so as to normally engage the tooth which is disposed beneath the tooth which the pin 26 engages. The block 22 is provided with forwardly projecting ears 29 beneath the pawl 27, and the inner end of the lever 30 is pivoted to said ears and is pivotally mounted for vertical rocking movement upon a horizontal rod 31 which passes through the hub 32 of the lever 30 and which 25 is supported by the partitions 7 and the adjacent side wall of the casing 5. The lever 30 extends outwardly through a vertical elongated slot 33 provided in the front wall of the casing 5, and is provided upon 30 its free end exteriorly of the casing with a finger-piece 34 adapted to be engaged by the finger for depressing the lever 30 so as to cause upward sliding movement of the block 22. It will be understood that 35 when the lever 30 is depressed for a certain distance, the pin 26 will cause sufficient rotary movement of the drum 12 for allowing one match to drop from said drum, while if the lever 30 is depressed further, the 40 spring pressed pawl 27 will effect a further rotation of the drum 12 for causing another match to be delivered immediately after the delivery of the first match. As the pawl 27 is positioned normally in a vertical plane 45 inwardly of the vertical plane of the periphery of the ratchet wheel 21, it is necessary that the same yield rearwardly when the block 22 is forced upwardly, and said pawl 27 is therefore formed of resilient sheet metal and is spaced from the block 22 so 50 as to permit this yielding. The bottom of the casing 5 is forwardly and downwardly inclined and terminates in a pocket 35 adjacent the front wall of the receptacle 5 where said front wall is provided with an 55 opening 36 of sufficient size to permit the entrance of a person's hand for removing the matches as they are delivered from the hopper 16 by the drum 12 to the pocket 35. 60 It will thus be seen that I have provided an extremely efficient means for delivering one or two matches at a time, as desired and at will. The grooves 15 of the drum 12 are laterally enlarged or widened at their ends 65 as at 15 so as to accommodate the heads

of the matches, no matter at which side of the drum the head of the match is situated.

The partition 7 has a bell or sound producing shell 37 fastened thereto above the ratchet wheel 21, and a lever 38 is pivotally mounted on the partition 7 beneath said shell 37 so that its lower end is normally pressed into engagement with the teeth of the ratchet wheel 21 by means of a leaf spring 39 which is carried by the front wall 75 of the receptacle 5 and which has its free lower end bearing upon said lever 38, the other end of the lever 38 having a hammer 40 secured thereto and lying close to the shell 37 so that when the ratchet wheel 21 80 is rotated, the hammer 40 is forcibly pressed against the shell 37 for sounding an alarm upon each delivery of a match from the drum 12. This alarm is somewhat useful when the present device is used in public 85 places where mischievous persons are likely to make improper use of the same and enables a proprietor to be advised of such improper use should the same occur.

From the foregoing description, it is believed that the construction and operation of the present invention, as well as the advantages of the same, will be readily understood and appreciated by those skilled in the art.

Minor changes may be made without departing from the spirit and scope of the invention as claimed.

What is claimed as new is:

A match delivering receptacle comprising 100 a casing having a front wall with a vertical elongated slot in the lower portion thereof and provided with a transverse partition dividing the casing into an upper hopper and a lower chamber therebeneath, a drum 105 journaled upon a horizontal axis within said lower chamber and having peripheral grooves arranged to receive matches from said hopper and to deliver the same to said lower chamber when rotated, a vertical partition within said casing forming a chamber at one side of said drum and said hopper, a ratchet wheel connected with said drum so as to rotate with the latter and arranged within the last named chamber, a slide block 110 vertically movable within the last named chamber and normally spring pressed in a lowered position, a rigid pawl carried by said slide block and operatively associated with said ratchet wheel so as to be capable 115 of only rotating said drum a distance sufficient for delivering one match from said hopper to said lower chamber upon each upward movement of said slide block, a second pawl carried by said slide block and comprising a resilient sheet metal strip having an angularly bent upper end associated with said ratchet wheel so as to cause sufficient 120 rotation of said drum for delivering a plurality of matches from the hopper to the 125 130

lower chamber each time the slide block is entirely elevated, and a finger actuated lever connected to said slide block and extending through the slot of the front wall of the 5 casing whereby said slide block may be caused to totally or partially raise for effecting delivery of either a single match or a

plurality of matches into the lower chamber at will.

In testimony whereof we affix our signatures.

SZYMON SLOBODZIAN.
JOZEF OBERLEYTAN.
